DESIGN FOR A FRYING PAN

William Hallgarth, Hatboro, Pa., assignor of
one-half to Marvin L. Gill, Lansdale, Pa.

Application July 16, 1946, Serial No. 131,603

Term of patent 14 years

(Cl. D44—1)

To all whom it may concern:

Be it known that I, William Hallgarth, a citizen of the United States, residing at Hatboro, in the county of Montgomery and State of Pennsylvania, have invented a new, original, and ornamental Design for a Frying Pan, of which the following is a specification, reference being had to the accompanying drawing, forming a part thereof.

Figure 1 is a perspective view of a frying pan, showing my new design.

Figure 2 is a sectional view taken along the line 2—2 of Figure 1.

I claim:

The ornamental design for a Frying Pan, as shown.

WILLIAM HALLGARTH.
